UNITED STATES PATENT OFFICE.

SIMON W. WARDWELL, OF PROVIDENCE, RHODE ISLAND, ASSIGNOR TO
UNIVERSAL WINDING COMPANY, OF PORTLAND, MAINE, A CORPORA-
TION OF MAINE.

DESIGN FOR A COP OR THREAD PACKAGE.

SPECIFICATION forming part of Design No. 35,423, dated December 10, 1901.

Application filed October 21, 1901. Serial No. 79,487. Term of patent 14 years.

To all whom it may concern:

Be it known that I, SIMON W. WARDWELL, a citizen of the United States, residing at Providence, in the county of Providence and 5 State of Rhode Island, have invented and produced a new and original Design for a Cop or Thread Package, of which the following is a specification, reference being had to the accompanying drawings, forming part thereof.

10 The essential feature of my design consists in a cop or thread package having a substantially cylindrical body portion and tapering or conical ends, the body portion presenting an ornamental appearance, all as 15 hereinafter set forth.

In the accompanying drawings, Figure 1 is a side view of a cop or thread package embodying my design. Fig. 2 is a similar view of the opposite side of the cop or thread pack- 20 age, and Fig. 3 is an end view thereof.

The surface of the body portion A of the

cop or thread package presents a pattern embracing ribbed triangular portions or figures a b, the apices of which are opposite each other, and ribbed side portions c c' upon opposite sides of the triangular figures, the side portions c filling the spaces between the said figures and the conical ends d d. The ends d d show a corded configuration disposed in a volute which starts at e from a naval-like 25 origin.

What I claim is—

The design for a cop or thread package, substantially as shown.

In testimony whereof I have signed my 35 name to this specification in the presence of two subscribing witnesses.

SIMON W. WARDWELL.
